UNITED STATES PATENT OFFICE.

JAMES L. LAZELLE, OF JERSEY CITY, NEW JERSEY.

CIRCUIT-CLOSER FOR BURGLAR-ALARMS.

SPECIFICATION forming part of Letters Patent No. 289,665, dated December 4, 1883.

Application filed September 10, 1883. (No model.)

To all whom it may concern:

Be it known that I, JAMES L. LAZELLE, of Jersey City, in the county of Hudson and State of New Jersey, have invented an Improvement in Circuit-Closers for Burglar-Alarms, 5 of which the following is a specification.

This invention relates to a rotary circuit-breaker adapted to burglar-alarms, &c., for ascertaining the location where the window or 10 door has been opened.

This invention consists in a disk of insulating material upon a spindle and an arc of metal having radial ends passing into notches in the insulated disk, whereby the arc is held 15 very firmly. I use circuit-closing springs and stops in connection with this disk and conducting-arc.

In the drawings I have represented in Figure 1 an elevation of the apparatus, in Fig. 2 a section of my rotary circuit-breaker, in Fig. 3 a rear view of the same, and in Fig. 4 a diagram of the circuit-connections.

The disk *a* is of insulating material, such as vulcanite or gelatinized fiber. This is connected to the spindle *b* by a square and nut, *c*, and this spindle *b* passes through the insulating-plate *d* and terminates with a button, *f*, and it will generally also have a hand or pointer, *e*, and there will be marks upon the 30 face of the instrument to indicate the electric circuit to be open or closed, and the burglar-alarm to be "on" or "off." It is preferable to have a metal bushing, *g*, in the plate *d* for the spindle *b* to turn in, as shown in Fig. 2. The pins *i*, upon the edge of the disk *a*, come into contact with the stop 3 and limit the movements of the circuit-breaker as it is turned in one direction or the other. The edge of the disk *a* is notched radially in two places, and 35 the conducting-arc *o* is made with two radial ends entering these notches. This conducting-arc is hence very easily and firmly affixed to the edge of the disk by simply pressing it laterally into place, and there may be two or 40 more of these conducting-arcs on each disk. There are two spring-contacts, *h* and *k*, to each disk *a*, the ends of the springs preferably 45 pointed toward each other, and their points of attachment being secured to the insulating-plate *d*. It will now be seen that when the circuit-breaker is turned by its button in one direction the conducting-arc will be moved from

beneath one or both the contact-springs *h* and *k* and break the circuit. The reverse movement will close the circuit, and the parts rubbing upon each other keep the surfaces clean. 55

The bell *L* is of ordinary character. It will usually be provided with an electro-magnet and circuit-breaking armature to the hammer, so as to ring continuously while the circuit is closed. 60

The wire 5 is to be regarded as the positive wire running to the base-plates of all the circuit-closing window and door springs in the burglar-alarm system. 65

The wire 6 is to be connected to all the springs in the circuit-closers on one floor or in one room, as the case may be. It thence passes to the binding-post 22 and spring *h* in the rotary circuit-breaker allotted to that section of the house—say the "parlor"—then by the spring *k* to the binding-screw 8 and magneto-bell *L*, and then by the return-wire or ground 7 to the battery. In like manner the wire 10 passes from the springs in the circuit-closers of the next group—say those used in the "kitchen"—to the binding-screw 32 and rotary circuit-closer having the corresponding or appropriate mark, thence to the binding-screw 8 and magnet of the bell, and to the 80 ground or return circuit. 75

The wire 12 is shown as passing from the springs in a third group of window-springs marked "library," thence to the binding-screw 42 and rotary circuit-closer and to the bell. 85

The wire 13 is shown as passing from the springs in the fourth group of window-springs marked "dining-room," thence to binding-screw 52, rotary closer, and magneto-bell. By this arrangement the bell will be rung by either 90 circuit-closing window-spring when acted upon by a burglar, and the party whose attention is called by the bell will move first one circuit-breaker and then the other until the bell stops ringing. He then knows by the position of 95 the circuit-breaker which room or place has been entered, and he acts accordingly. This arrangement of branch circuits and circuit-breakers between the groups of window-springs and bell is not dependent upon my peculiar 100 rotary circuit-breaker, but may be used with switches to open and close the circuit.

I claim as my invention—

1. The electric-circuit breaker formed of the

disk *a*, of insulating material, notched radially in its edge, and the conducting-arc with radial ends connected with such disk by its radial ends passing into the notches, the supporting-spindle passing into such disk, and the button *f*, by which the circuit-breaker is turned, substantially as specified.

2. The disk *a*, of insulating material, notched radially in its edge, and the conducting-arc with radial ends connected with such disk by its radial ends passing into the notches, the supporting-spindle passing into such disk, and

the button *f*, by which the circuit-breaker is turned, in combination with the insulated springs connected in the electric circuit, and the stops for limiting the motion of the electric-circuit breaker, substantially as specified. 15

Signed by me this 6th day of September, A. D. 1883.

J. L. LAZELLE.
